STRIP FEEDING MECHANISM

Cecil E. Adams, Columbus, Ohio, assignor to The Denison Engineering Company, Columbus, Ohio, a corporation of Ohio

Application November 2, 1948, Serial No. 57,929

13 Claims. (Cl. 271—2.5)

This invention relates generally to machine tools and more particularly to mechanism for feeding strip stock to apparatus for performing operations thereon, one type of such apparatus being a press.

An object of the invention is to provide a strip feeding mechanism, which will function as an accessory for a punch press and be operated in sequence therewith, by having a direct connection with the driving mechanism of the press.

Another object of the invention is to provide a feeding mechanism for strip material, such mechanism having a stock advancing carriage which will be operated with a harmonic motion, the carriage being uniformly accelerated and decelerated during movement in both directions, that is, when moving the strip stock toward the press and when moving in a reverse direction to secure a new purchase on the strip material.

A still further object of the invention is to provide a strip feeding mechanism having a carriage disposed for reciprocatory movement and an eccentric driven by the driving mechanism of a press to which the feeding mechanism is applied, motion transmitting means being arranged between the carriage and the eccentric to transform the rotary motion of the eccentric into linear motion on the part of the carriage.

A further object of the invention is to provide a strip feeding mechanism of the type mentioned in the preceding paragraph, with means for gripping the strip stock during the advance movement of the carriage, the gripping means being operated by certain movements of the motion transmitting means between the eccentric and the carriage.

Another object of the invention is to provide a strip feeding mechanism having a reciprocating slide or carriage, on which is arranged a stock gripping means, and means for imparting movement to the carriage, such means including a rotary eccentric or crank and a connecting rod, the latter swinging back and forth, as the crank rotates, and transmitting linear movement to the carriage, the swinging movement of the connecting rod being utilized to operate the stock gripping means, the latter being so constructed and arranged that it will be operated to grip and release the stock at the ends of the reciprocatory strokes of the carriage when the linear motion thereof has substantially ceased.

It is also an object of the invention to provide mechanism of the character set forth in the preceding paragraph with stock gripping means powered by springs and having means, operated by the eccentric crank and connecting rod utilized to transmit motion to the carriage of the mechanism, to retract the jaws of the gripping means against the force of the springs when the carriage is at one extremity of its travel and exposes the jaws to the force of the springs when the carriage is at the other extremity of its travel, the clamping and unclamping of the jaws taking place when the connecting rod is swinging at its fastest rate which will be at the time the carriage is stationary or moving at a substantially imperceptible rate.

Further objects and advantages of the present invention will be apparent from the following description, reference being had to the accompanying drawings wherein a preferred form of embodiment of the invention is clearly shown.

In the drawings:

Fig. 1 is a front elevational view of a mechanical press

2

provided with strip feeding mechanism formed in accordance with the present invention.

Fig. 2 is a vertical transverse sectional view taken through the strip feeding mechanism on the plane indicated by the line II—II of Fig. 1.

Fig. 3 is a detail horizontal sectional view taken through the mechanism on the plane indicated by the line III—III of Fig. 1.

Fig. 4 is a vertical longitudinal sectional view taken through the strip feeding mechanism on the plane indicated by the line IV—IV of Fig. 2, this view showing the strip feeding mechanism at the end of an advanced stroke.

Fig. 5 is a similar view showing the mechanism during the retraction stroke of the carriage.

Fig. 6 is a detail vertical sectional view taken through the stationary stock gripping mechanism forming a part of the feeding mechanism.

Fig. 7 is a detail horizontal sectional view taken through the stock gripping mechanism on the plane indicated by the line VII—VII of Fig. 6.

Figs. 8, 9, 10, and 11, are plan views partly in section of the feeding mechanism showing the same in different stages of operation.

Referring more particularly to the drawings and especially to Fig. 1, the numeral 20 designates a mechanical press of the rotating crank type. The press 20 may be of many types, the one shown being selected merely for the purpose of illustrating the invention and not by way of limitation. This press 20 includes a frame 21, having side members 22, which are connected by suitable cross members 23. The side members are equipped with guides 24 in which a cross head 25 slides, this cross head constituting the ram of the press and furnishing a mounting for tools, or, other equipment used to perform operations on material supplied to the press. The cross head 25 is connected to one end of a connecting rod 26, the opposite end of this member being pivotally supported by a crank shaft 27 which is journaled in bearings 28 at the upper ends of the side members 22.

One end of this crank shaft is equipped with a pulley 30, which may also be weighted to serve as a fly-wheel and belt means 31 extends around the pulley 30 and transmits rotary motion from a driving motor 32 to the crank shaft 27. The opposite end of the crank shaft is provided with a bevel gear 33, this gear being disposed in meshing relation with a similar gear 34 mounted on the upper end of a countershaft 35 this countershaft is supported for rotation in bearings 36 secured to one end of a side member 22. The mechanism thus far described is shown merely for the purpose of indicating a mechanical press and is not intended to limit the present application, the application being directed to a strip feeding mechanism for use in connection with any kind of a press.

The lower end of the shaft 35 carries a block 37, in which a dovetail slot 38 is formed in the under side. This slot 38 receives the head 40 of a crank pin 41, the shank end of which projects through one end of a connecting rod 42, the crank pin is provided with a nut 43 and washer 44 to prevent the separation of the connecting rod 42 therefrom. This connecting rod is formed at the opposite end with a threaded opening 45 and is split as at 46, so that it may be rigidly but adjustably secured to the end of a sleeve 47, this sleeve being provided with fast lead internal screw threads 48. These screw threads receive similar threads 50 provided on the shank of a clevis bolt 51, this member having a bifurcated end 52 through which pins 53 extend. The end 52 of the member 51 is arranged to straddle a bar-like gripping jaw 54, which is provided with slots 55 through which the pins 53 also project. The end portions of the jaw are formed with sockets 56 to receive and locate the lower ends of compression springs 57, the upper portion of these compression springs being disposed in openings 58 formed in a boss 60 provided on a plate-like carriage body 61. As shown in Fig. 2 this carriage body has bevelled sides 62 for engagement by cap strips 63, which are secured to the upper edges of side rails 64 formed on the body 65, constituting the support for the strip feeding mechanism,

80 the side portions of the carriage 61 resting upon the upper surfaces of the side rails and are held for sliding move-

ment thereon by the cap strips 63, the strips and the side rails forming ways in which the carriage may slide.

A second stock gripping jaw 66 is secured to the under side of the carriage 61, this jaw being disposed in registration with the movable jaw 54. Since both jaws are mounted on the carriage they will move therewith when the carriage is reciprocated. Jaw 54 is guided for movement toward and away from jaw 66, the former being moved toward the latter by springs 57 and away therefrom in opposition to the force of the springs by the rotation of the sleeve 45 and the reaction of the threads 48 with the threads 50 on the clevis pin. The jaws are shown in stock gripping position in Fig. 4 and in open or stock releasing position in Fig. 5. Rotary movement of the sleeve 45 to effect the movement of jaw 54 is caused by the swinging movement of the connecting rod or lever 42 in response to the rotation of shaft 35 and block 37.

The body 65 of the strip feeding mechanism may be secured in any desirable manner to the frame of the press 20, or it may be supported by an independent framework. It includes a plate-like base section 67 and the side rails 64 extending longitudinally thereof. At a point adjacent the outer ends thereof, the side rails 64 are provided with openings 68 for the reception of the end portions of the gripping rolls 70; the side rails are also provided with horizontal openings 71 as illustrated in Figs. 6 and 7, which receive spring pressed plungers 72. These members engage the end portions of the rolls 70 and urge them toward the outer end of the side rails. When the rolls are urged in this direction, the concave surfaces of the openings 68 will cause the rolls to be moved toward one another and grip strip material inserted therebetween. In some instances it is desirable to effect opening movement or separation of these rolls and this operation is accomplished through the rotation of a rod 73 also extending between and journaled in the side rails; this rod 73 is provided with cam surfaces 74, which cooperate with ball elements 75 disposed in registration therewith. These ball elements engage the rolls 70 and force such rolls apart when moved toward the same through the rotation of the rod 73. This rod may be manually rotated through the oscillation of pin 76 projecting therefrom at the exterior of one of the side rails. The rolls may be mechanically separated in the event it is desired to release the stock during, or immediately prior to a forming operation thereon, through the provision of a second transverse rod 77 at the front portion of the body 65; this rod having a lever 78 secured to the ram end thereof and adapted to be engaged by the ram of the press, or, an element movable therewith. Suitable motion transmitting means 80 extends between the rod 77 and the rod 73, so that when the rod 77 is rocked, due to the engagement of the lever 78 by the ram or its equivalent, rod 73 will also be rocked to move ball elements 75 between rolls 70 to effect their separation.

It should be obvious from the foregoing description taken in connection with the accompanying drawings that when the crank shaft of the press is revolved, the shaft 35 will be rotated; this rotary movement will cause the rotation of the block 37 about the axis shaft 35 and crank pin 41 will be revolved or moved in a circle therewith. Since this crank pin is connected to the outer end of the lever 42, this end of the lever will be swung about the axis of the clevis pin 51. Due to the rotary movement of the crank pin, the carriage 61 will be reciprocated in its ways toward and away from the press 20. By reason of the swinging movement of the lever 42 and the provision of the threaded connection between the sleeve 45 and clevis bolt 51, the jaw 54 will be moved toward and away from the jaw 66. The thread is so calculated and the lever so adjusted on the sleeve 47 that when the carriage is located most remotely from the press the jaw 54 will be just lightly touching the stock.

It will be observed that the reaction of the threads in the sleeve 47 with those on the clevis bolt 51 continues as long as connecting rod 42 is swinging and that the sleeve 47 revolves in one direction when the outer end of the lever 42 swings toward one side of the longitudinal axis of the feeding mechanism and in the opposite direction when the lever swings toward the other side. From a comparison of Figs. 8 to 11, inclusive, it will be seen that when the carriage is at the mid-point of a reciprocatory stroke in one direction the lever 42 will be disposed as far toward one side of the longitudinal center of the

feeding mechanism as it may swing and when the carriage is disposed at the same point while moving in the opposite direction the lever will be disposed at the extreme point on the opposite side of the center. Since the crank pin 41 moves in a circular path it and the lever 42 will gradually slow down until the point of direction reversal is reached then the motion will gradually increase. These members will be moving rapidly when the carriage reaches the points at which the direction of movement thereof is reversed.

The slots 55 are provided in the jaw 54 to permit the over travel of the clevis bolt 51 after the jaw 54 has engaged the stock during a clamping operation. It is desirable to have the jaw 54 engage the material when the carriage is stopped at the end of its retractive movement and immediately before starting its advance stroke. To accomplish this timing the threaded connection between the connecting rod 42 and sleeve 47 has been provided; by loosening the clamp screw in the end of lever 42, the sleeve 47 may be adjusted until the jaw just barely touches the material after which the clamping screw in lever 42 may be tightened to secure the lever and sleeve in adjusted relation. This adjustment also compensates for differences in thickness of material being fed by the mechanism. As the lever 42 continues to move beyond the position shown in Fig. 10, the clevis bolt 51 will continue to move toward the stock and jaw 54 will be urged by springs 57 into gripping engagement with the stock. The gripping action continues until the carriage has just about reached the end of its advancing stroke even though the clevis bolt 51 started to move upwardly when the crank pin 41 rotated more than ninety degrees from the position shown in Fig. 10 or beyond the position shown in Fig. 11. When the carriage is in the most advanced position, shown in Fig. 8, the jaw 54 will be just touching the stock. The clevis bolt 51 will, however, be moving in an upward direction and as the swinging movement of lever 42 continues the pins 53 carried by the bolt 51 will engage the ends of the slots 55 and move the jaw 54 away from the stock. The continued movement of the lever 42 also causes the carriage to retract but as the jaw 54 has been released from the stock the latter will not be moved rearwardly. The stock is also held against movement in this direction by the gripping rolls 70, the movement of the stock in this direction tending to move the rolls 70 into tighter clamping relationship. Movement of the stock in a forward direction by the movable jaws and carriage has the opposite effect on the gripping rolls 70, since movement of these rolls toward the press will permit the rolls to separate and release the stock. These rolls will, therefore, offer little, or, no resistance to the feeding of the stock to the press. It should be obvious from an inspection of Fig. 3 that the crank pin 41 may be adjusted longitudinally of the slot 38 to vary the distance between the crank pin and the axis of rotation of the shaft 35 when it is desired to vary the amount of stock fed on each reciprocation of the carriage. The timing of this feeding operation relative to the stroke of the ram will be determined by the angular relation between the shaft 35 and the block 37. Since gears 33 and 34 are duplicates shaft 35 will revolve at the same rate as crank shaft 27, the feeding strokes will, therefore, occur in properly timed relation with the pressing strokes of the ram, or, frequency of operation of the latter. The ram may thus be manually controlled through the operation of a suitable clutch without affecting the sequence of operation of the ram and feeding mechanism.

While the form of embodiment of the present invention as herein disclosed constitutes a preferred form, it is to be understood that other forms might be adopted, all coming within the scope of the claims which follow:

I claim:

1. Strip feeding mechanism comprising a base; a carrier supported for reciprocation on said base; strip stock gripping means provided on said carrier; driving means for said mechanism having a rotary shaft; an eccentric operated by said rotary shaft; a connecting rod pivotally secured to said eccentric and said carrier; said connecting rod transmitting motion from said eccentric to said carrier to cause reciprocation thereof; said eccentric serving to rock said connecting rod about an axis on said carrier, and cam means between said connecting rod and said stock gripping means, the rocking motion of said connecting rod serving to actuate said cam means to control

the movement of said stock gripping means into and out of operative position.

2. Feeding mechanism comprising a base; a carrier supported for reciprocation on said base; stock gripping means provided on said carrier, said means having operating elements relatively movable about an axis; an eccentric element supported for rotation about a second axis disposed in parallel relation to the first-mentioned axis; and motion transmitting means connecting said eccentric element, said stock gripping means and said carrier, said motion transmitting means being disposed for simultaneous linear movement in a direction parallel to the direction of movement of said carrier and swinging movement laterally with respect to the movement of said carrier, said motion transmitting means utilizing the movement of said eccentric element to either side of a plane passing through the axis of rotation thereof at right angles to the path of movement of said carrier to reciprocate said carrier and the movement of said eccentric element to either side of a plane passing through such axis parallel to the path of movement of said carrier to control the operation of said stock gripping means.

3. Feeding mechanism comprising a base; a carrier supported for reciprocation on said base; stock gripping means provided on said carrier, said gripping means having cooperating threaded elements; an eccentric member supported for rotation about an axis disposed at right angles to the path of movement of said carrier; and a motion-transmitting lever connecting said eccentric member and said carrier, said motion-transmitting lever being connected with said carrier through one of the threaded elements of said gripping means for pivotal movement about the axis of the threaded elements and utilizing the movement of said eccentric member laterally with respect to the path of movement of said carrier to control the operation of said stock gripping means and the movement of said eccentric member longitudinally of the path of movement of said carrier to effect the movement of such carrier.

4. Feeding mechanism comprising a base; guide means provided on said base; a carrier supported for reciprocation in said guide means; a stationary jaw on said carrier; a second jaw disposed on said carrier for movement toward and away from said stationary jaw, said second jaw having a threaded member restrained against rotation; spring means tending to urge said second jaw toward said stationary jaw; a second threaded member cooperating with said first-mentioned threaded member, said second threaded member being supported for rotary movement; a crank pin supported for orbicular movement about an axis extending parallel to the axis of said threaded member; and a connecting rod secured at one end to said crank pin and at the other end to said second threaded member, the longitudinally component of the orbicular movement of said crank pin with respect to said guide means being transmitted to said carrier, and the transverse component of the orbicular movement of said crank pin with respect to said guide means serving to oscillate said second threaded member.

5. Feeding mechanism comprising a base; guide means on said base; a carrier supported for reciprocation by said guide means; a stationary jaw on said carrier; a second jaw disposed on said carrier for movement toward and away from said stationary jaw; spring means tending to urge said second jaw toward said stationary jaw; oscillatable means for moving said second jaw in opposition to said spring means; and operating means for simultaneously reciprocating said carrier on said guide means and actuating said jaw moving means, said operating means having a revolving crank and a member connected at one end to said crank and at the other to said oscillatable means.

6. Feeding mechanism comprising a base; guide means on said base; a carrier supported for reciprocation by said guide means; a stationary jaw on said carrier; a second jaw disposed on said carrier for movement toward and away from said stationary jaw; spring means tending to urge said second jaw toward said stationary jaw; oscillatable means for moving said second jaw in opposition to said spring means; and operating means for simultaneously imparting uniformly accelerated and decelerated motion to said carrier and said jaw moving means said operating means having a revolving crank and a member connected at one end to said crank and at the other end connected to said oscillatable

to said oscillatable means, the motion of said carrier and jaw moving means occurring ninety degrees out of phase.

7. Stock feeding mechanism comprising a base; a carrier guided for reciprocatory movement on said base; a stationary jaw on said carrier; a second jaw supported on said carrier for movement toward and away from said stationary jaw; relatively rotatable members on said carrier for imparting movement to said movable jaw; a crank supported for rotation about an axis disposed in spaced parallel relation to the axis of relative rotation of said members; and a link connected with said crank and one of said relatively rotatable members, rotation of said crank serving to simultaneously reciprocate said carrier and impart relative rotary movement to at least one of said members to actuate said movable jaw.

8. Stock feeding mechanism comprising a base; a carrier guided for reciprocatory movement on said base; a stationary jaw on said carrier; a second jaw supported on said carrier for movement toward and away from said stationary jaw; a first member disposed for rotary motion on said carrier; a second member connected with said movable jaw and responsive to rotary oscillations of said first member to actuate said movable jaw; a crank supported for rotation about an axis disposed in spaced parallel relation to the axis of rotation of said first member; and a link rigidly secured at one end to said first member and pivotally connected to said crank at the other.

9. Stock feeding mechanism comprising a base; a carrier guided for reciprocatory movement on said base; a stationary jaw on said carrier; a second jaw supported on said carrier for movement toward and away from said stationary jaw; resilient means tending to urge said second jaw toward said stationary jaw; a first member disposed for rotary motion on said carrier; a second member connected with said movable jaw and responsive to rotary oscillations of said first member to actuate said movable jaw in opposition to said resilient means; a crank supported for rotation about an axis disposed in spaced parallel relation to the axis of rotation of said first member; and a link rigidly secured at one end to said first member and pivotally connected to said crank at the other.

10. Stock feeding mechanism comprising a base; a carrier guided for reciprocatory movement on said base; a stationary jaw on said carrier; a second jaw supported on said carrier for movement toward and away from said stationary jaw; a first member disposed for rotary motion on said carrier; a second member responsive to rotary oscillations of said first member to move toward and away from said stationary jaw; a lost motion connection between said second member and said second jaw; a crank supported for rotary movement about an axis disposed in spaced parallel relation to the axis of rotation of said first member; and a link rigidly secured at one end to said first member and pivotally connected to said crank at the other end.

11. Strip feeding mechanism comprising a base; a carrier supported for reciprocation on said base; a stationary jaw on said carrier; a second jaw guided for movement toward and away from said stationary jaw; reaction means disposed on said carrier and movable jaw, a part of said reaction means being disposed for oscillatory movement to actuate said movable jaw; a shaft journaled for rotary movement; an eccentric crank secured for rotation with said shaft; and a rod member connected at one end to said crank and at the opposite end to the oscillatory part of said reaction means for rocking movement about the axis thereof, said eccentric crank moving said rod member in a direction parallel to the movement of said carrier to effect reciprocation thereof and rocking said rod member about the axis of oscillation of said reaction means to actuate said movable jaw.

12. Feeding mechanism comprising a base; a carrier supported for reciprocation on said base; stock gripping means provided on said carrier; an eccentric element supported for rotation about an axis disposed at right angles to the path of movement of said carrier; and a single member connecting said eccentric element, said carrier and said stock gripping means, the movement of said eccentric element on either side of a plane passing through the axis of rotation thereof at right angles to the path of movement of said carrier being transmitted by said single member to said carrier to cause the reciprocation thereof, the movement of said eccentric element on either side of

as plane disposed at right angles to the first plane being transmitted through said single member to said stock gripping means to control the operation thereof.

113. Feeding mechanism comprising a base, a carrier supported for reciprocation on said base, stock gripping means provided on said carrier, said means having operating elements relatively movable about an axis, an eccentric element supported for rotation about a second axis disposed in parallel relation to the first-mentioned axis, and a member connecting said eccentric element, 10 said stock gripping means and said carrier, said member being disposed for simultaneous linear movement in a direction parallel to the direction of movement of said carrier and swinging movement about the axis of movement of the operating elements of said stock gripping means, the movement of said eccentric element to either 15 said of a plane passing through the axis of rotation thereof at right angles to the path of movement of said carrier being transmitted by said connecting member to said

carrier to reciprocate the same, the movement of said eccentric element to either side of a plane passing through the axis of rotation of said eccentric parallel to the path of movement of said carrier swinging said connecting member about the axis of movement of the operating elements of said stock gripping means to control the operation thereof.
